(No Model.)

G. A. WILKINS.

MAGNETO ELECTRIC TELEPHONE CALL.

No. 361,737.

Patented Apr. 26, 1887.

UNITED STATES PATENT OFFICE.

GEORGE A. WILKINS, OF PHILADELPHIA, PENNSYLVANIA.

MAGNETO-ELECTRIC TELEPHONE-CALL.

SPECIFICATION forming part of Letters Patent No. 361,737, dated April 26, 1887.

Application filed April 16, 1884. Serial No. 128,176. (No model.)

To all whom it may concern:

Be it known that I, GEORGE A. WILKINS, a citizen of the United States, residing at Philadelphia, in the county of Philadelphia and State of Pennsylvania, have invented certain new and useful Improvements in Telephone-Calls, of which the following is a specification.

In most cases as now used in telephone systems the magneto calling apparatus is placed in a box and located above the transmitter upon a base-board, which is usually attached to the wall of the room. This makes it necessary for the subscriber to leave his desk and proceed to the telephone-instruments, and it often happens that he is unable to make immediate connection with the desired party, owing to many well-understood causes, and he has to remain standing for some time, or return from his seat again and again. Some attempts have been made to obviate this objection by attaching the telephone-instruments to the desk or to a swinging standard attached to the desk, so that the calling and telephone instruments can be swung around into a position to be used without leaving one's seat.

My invention relates to this class of telephone-calls, and has for its object to provide a simple, compact, and effectual apparatus, which may be placed upon the desk of the subscriber, or in convenient proximity to the desk, and adapted to be operated by the subscriber without leaving his seat, and at the same time to occupy very little space and practically be out of the way in using the desk.

To these ends my invention consists in a compact electric generator, in a substantially cylindrical form, supporting the bell-ringing devices and operating means, the whole being adapted to be inclosed in the hollow base of a telephone-supporting standard or bracket, which may be supported upon the subscriber's desk, or in convenient proximity thereto.

In the drawings, Figure 1 is a perspective view of the signaling or call apparatus. Fig. 2 is a vertical section of the same. Fig. 3 is a horizontal section. Fig. 5 shows the call apparatus inclosed in a standard supporting the telephone-instruments. Fig. 4 is a modified form of generator, and Fig. 6 shows a diagram of the circuits.

The magneto-generator may be of any suit-

able construction, that shown consisting, essentially, of one or more permanent magnets, A, preferably in the form of rings, and having inwardly-projecting pole-pieces B, between which is located the armature C, in this instance of the well-known Siemens form. These magnets are supported and held together between two plates by rods or bars D, fixed to the upper plate, E, the lower plate, F, being secured thereto by screws. The armature may be supported by these plates in any suitable manner, a hole in the plate E forming a bearing for one end of the armature-shaft C, the other end of which has its step in the plate F.

A shaft, H, carrying a large bevel gear-wheel, h, has its bearings in the bracket G and standard I, also secured to the plate F, and a small gear-wheel, c, secured to the shaft C, meshes with the gear-wheel h. The ends of the shaft H are squared or otherwise formed so as to be adapted to receive a crank, K, or other device by which the shaft is rotated, and a rapid motion communicated to the armature C by the gears h and c; also, upon the plate E is secured a horseshoe electro-magnet, L, having suitable coils upon its poles, and loosely mounted upon the shaft H is a polarized armature, M, adapted to be oscillated thereon by the magnet, and arranged below, so as to strike the bell N, secured to the standard G. The armature may be provided with lugs or projections, if desired, as indicated in dotted lines, to form bell-hammers, or the ends of the polarized armature may operate directly thereon.

Upon an insulating-piece, O, are the binding-posts a b, the former being provided with a screw, d, and the latter connected with a spring-piece, e, normally bearing against the screw d, and forming a short circuit, as hereafter explained.

A suitable circuit-breaker may be supported in the standard f, that shown consisting of a pin, W, having an end of insulating material resting upon the spring e and a push-knob at the other end.

Suitable collecting brushes or connections, k l, bear upon the armature-shaft C, and are electrically connected with the bobbin or coil of the armature and the binding-posts a b of the electro-magnet.

This call apparatus is preferably inclosed in

a case which may form the base of a standard supporting the telephone-instruments, and this may be in any convenient form. As shown, it consists of a hollow base, P, inclosing the call apparatus, having openings on each side for the insertion of the crank K, and an opening for the passage of the circuit-breaking push-button, while from the upper part projects an arm, Q, carrying the telephone-instruments

10 T.R.

The arrangement of circuits is shown diagrammatically in Fig. 6, and the operation will readily be understood therefrom. The line in circuit is shown as being connected to 15 any of the ordinary automatic switches that normally cut out the telephones and make connection with the signaling apparatus, the circuit being from the contact or bell binding-post *l* to the coils of the magnet, to the binding-post *b*, through the spring circuit-breaker *e*, to post *a*, and to ground or the next station on the line. In this position the signal apparatus is in condition to receive signals from 20 distant stations and the telephones and generator are cut out of circuit. If the subscriber 25 wishes to signal, he presses the button, breaking the contact between *e* and *d*, and operates his generator by the crank, which causes alternating currents to flow through the magnet-coils and operate the polarized armature to 30 ring the bell.

A modified form of magnets and arrangement of armature is shown in Fig. 6, the essential features being substantially the same 35 as those above described.

In either case the construction is such as to leave a space in which to put one or more battery-cells, O, for operating the telephone-transmitter, and in this connection I prefer to use 40 the chloride-of-silver cells, as they occupy little space and furnish the requisite current.

Various other modifications will be apparent and embraced within the scope of my invention.

45 The circuit-breaker, instead of being operated by a push-button, may be automatically operated upon attaching or turning the crank, and the electro-magnet coils may face each other and vibrate an armature located between 50 them.

By this construction and arrangement of devices it will be seen that I produce a very simple, compact, and durable call apparatus, that is well adapted to be used upon a subscriber's desk, or adjacent thereto, as it allows 55 of use by the subscriber without moving from his seat, and by using the automatic switch

the device can be operated by a single hand and from either side.

I claim—

60 1. A telephone-call apparatus consisting of a magneto-generator, electro-magnet connected therewith, a bell adjacent to the armature of the magnet, a circuit-breaker, and means for rotating the armature, all supported upon the generator, substantially as described.

65 2. The combination, with the generator having superposed magnets and an interior vertical armature, of a cap-plate having bearings for the armature and for the shaft, said shaft carrying a bevel-wheel gearing with a bevel-pinion on the armature-shaft, an electro-magnet connected with the generator, and an armature therefor arranged between the magnet and bell, substantially as described.

70 3. The combination of the generator, the cap-plate carrying an electro-magnet and provided with bracket G and standard I, arranged to afford bearings for the armature-shaft C, and driving-shaft H, and to support the bell N, substantially as described.

75 4. The combination of a generator, electro-magnet, bell, driving shaft H, geared with the armature of the generator, and armature M, of the electro-magnet hung to vibrate upon the shaft H, substantially as described.

80 5. A telephone-call provided with a generator having magnets of a substantially-circular form and inclosing a space within which is arranged one or more battery-cells, substantially as described.

85 6. The combination of a standard having a hollow base, a magneto call apparatus inclosed therein, and an arm adapted to support the telephone-instruments, substantially as described.

90 95 7. The combination of a hollow base, P, a magneto call inclosed therein, and arm Q, pivotally connected to said base and supporting transmitting and receiving instruments, the whole being adapted for attachment to a desk, substantially as described.

100 8. The combination, with a horseshoe-magnet having re-entering ends, of an armature located between the ends, substantially as described.

105 In testimony whereof I have signed my name to this specification in the presence of two subscribing witnesses.

GEO. A. WILKINS.
